SUPPORTING AND POSITIONING MEANS FOR FLANGE OILER PIPES AND NOZZLES

Filed August 3, 1923

Inventor:

Frank W. Edwards

by

W. H. Sinclair

Attorney.

UNITED STATES PATENT OFFICE.

FRANK W. EDWARDS, OF CHICAGO, ILLINOIS.

SUPPORTING AND POSITIONING MEANS FOR FLANGE-OILER PIPES AND NOZZLES.

Application filed August 3, 1923. Serial No. 655,483.

To all whom it may concern:

Be it known that I, FRANK W. EDWARDS, a citizen of the United States, residing at Chicago, in the county of Cook and State 5 of Illinois, have invented a certain new and useful Improvement in Supporting and Positioning Means for Flange-Oiler Pipes and Nozzles, of which the following is a full, clear, and exact description.

- 10 In installing flange oilers upon locomotives, it is desirable to provide some means for correctly supporting and positioning the flange oiler nozzles and their feed pipes in predetermined desired relation to the flanges 15 of the drive wheels of the locomotive, so that the installation of the flange oiler may be made by others than skilled mechanics without sacrificing anything of efficient operation.
- 20 To this end, the object of my invention is to provide a bracket, which may assume a variety of forms to adapt it for connection with a supporting portion of the locomotive adjacent to a drive wheel thereof, but which, 25 no matter in what form it may be, is previously so formed as to properly support and position the flange oiler nozzle and its feed pipe so as to direct the oil emitted from the nozzle upon the flange of the drive wheel 30 at a point thereon calculated to best serve the purpose of lubrication. In furtherance of this object, the nozzle itself is provided with means cooperating with the bracket for correctly supporting and positioning the 35 nozzle with relation thereto.

The invention consists in means for supporting and positioning flange oiler pipes and nozzles comprising a bracket or similar support adapted to be attached to a part 40 of a locomotive or similar vehicle adjacent to a drive wheel thereof, and a nozzle carried by a feed pipe, the nozzle and bracket being provided with cooperating means whereby, when the bracket is properly positioned, the nozzle will assume a predetermined relation thereto and consequently to the drive wheel, and means carried by the bracket and cooperating with the feed pipe 45 for maintaining the nozzle and bracket in such predetermined relative position, as I will proceed now to explain and finally claim.

In the accompanying drawings illustrating the invention, in the several figures of 50 which like parts are similarly designated,

Figure 1 is a fragmentary side elevation of a portion of a locomotive frame and drive wheel with my invention applied thereto. Fig. 2 is an end view of the parts shown in Fig. 1 and looking toward the right of Fig. 1. Fig. 3 is a section on the line 3-3 of Fig. 1. Fig. 4 is an enlarged fragmentary sectional elevation looking down upon the nozzle and showing its arrangement with respect to the drive wheel. Fig. 5 is an enlarged perspective view of the nozzle.

Referring more particularly to the drawings, 1 is a portion of a locomotive side frame carrying a transverse member 2, and in the installation of the invention as shown 50 I bolt to this member 2, as by bolts 3, a bracket 4 extending downwardly into close proximity to the tread of the drive wheel 5. This bracket is preferably cut away as shown at 6, Fig. 2, to form a clearance for the discharge end of the oiler nozzle 7, and its lower end is turned laterally towards the drive wheel to form a seat 8 upon which the nozzle may rest. This oiler nozzle is provided with wings or bosses 9 standing off from its body 80 portion and having bracket contacting faces arranged at an angle to its center line, and is carried upon the end of a feed pipe 10 extending from the lubricator, and which supplies oil to the nozzle. This pipe 10 is securely bolted against the bracket 4 by means of hook bolts 11 which pass through the bracket 4 and hook around the feed pipe 10 (see Fig. 3), so that when the nozzle is 85 in position resting upon the seat 8 and the hook bolts are tightened upon the pipe 10, that wing or boss of the nozzle which lies adjacent to the side of the bracket will be drawn tightly against the bracket and the nozzle thereby so positioned that the oil emitted therefrom will be directed upon that portion of the drive wheel flange 5' which affords the maximum of lubricating effect.

It will be noted that I provide the nozzle with two wings or bosses 9, one on each side thereof. This is done so that the nozzle may be used for either right or left hand installation, whereas if only one wing or boss were provided the nozzles would have to be made in "rights" and "lefts."

It will be apparent that for a certain type of locomotive, say for example, that type which has the member 2 as shown in the drawings, if holes for the bolts 3 are drilled in this member 2 at predetermined points 100 105 110

therein, and holes are made in the bracket 4 at points which when alined with the holes in the member 2 will correctly position the seat 8 of the bracket with respect to the drive 5 wheel, any bracket so drilled will, when bolted to the previously drilled member 2 of the locomotive, be so arranged with relation to the drive wheel of the locomotive as to correctly position the flange oiler feed pipe 10 and nozzle, when the same are applied to the bracket, as hereinabove described, thereby avoiding the possibility of mistakes in installing the flange oiler nozzle with respect to the drive wheel.

15 It is to be understood that I do not consider the invention as limited to the particular embodiment shown and described, as it is obvious that various changes may be made therein without departing from the spirit 20 of the invention or the scope of the following claims.

What I claim is:—

1. In a supporting and positioning means for flange oiler pipes and nozzles, a bracket 25 arranged to be supported in predetermined relation to a locomotive or other vehicle wheel, and a flange oiler nozzle provided with bracket contacting means comprising bosses arranged on opposite sides of said 30 nozzle and having bracket contacting faces arranged at an angle to the center line of said nozzle for positioning said nozzle in predetermined relation to said wheel.
2. In a supporting and positioning means 35 for flange oiler pipes and nozzles, a bracket arranged to be supported in predetermined relation to a locomotive or other vehicle wheel, and a flange oiler nozzle having laterally extending bosses arranged on opposite 40 sides thereof and provided with bracket contacting faces arranged at an angle to the center line of said nozzle for positioning said nozzle in predetermined relation to said wheel.
3. In a supporting and positioning means 45 for flange oiler pipes and nozzles, a bracket arranged to be supported in predetermined relation to a locomotive or other vehicle wheel, a flange oiler nozzle, and means on said bracket and cooperating means carried 50 by said nozzle comprising members of predetermined angularity with respect to said nozzle for positioning said nozzle in pre-

determined fixed angular relation to said wheel.

4. In a supporting and positioning means for flange oiler pipes and nozzles, a bracket arranged to be supported in predetermined relation to a locomotive or other vehicle wheel, a flange oiler nozzle, and means for fixedly locating said nozzle relatively to said wheel including a seat on said bracket and upon which the nozzle rests and a boss on said nozzle contacting with said bracket, said boss determining the angular relation of 65 the nozzle to the bracket.

5. In a supporting and positioning means for flange oiler pipes and nozzles, a bracket arranged to be supported in predetermined relation to a locomotive or other vehicle 70 wheel, a flange oiler nozzle, means on said bracket and cooperating means on said nozzle comprising members of predetermined angularity with respect to said nozzle for positioning said nozzle in predetermined fixed angular relation to said wheel, and means for fixedly but detachably clamping said nozzle upon said bracket.

6. In a supporting and positioning means for flange oiler pipes and nozzles, a bracket arranged to be supported in predetermined relation to a locomotive or other vehicle wheel, a flange oiler nozzle, an oil feed pipe communicating with said nozzle, cooperating means on said bracket and nozzle for positioning said nozzle in predetermined angular relation to said wheel, and means for clamping said pipe in fixed relation to said bracket for the purpose of maintaining the cooperating means on the bracket and nozzle in 80 predetermined relation to each other.

7. In a supporting and positioning means for flange oiler pipes and nozzles, a bracket arranged to be supported in predetermined relation to a locomotive or other vehicle wheel, a flange oiler nozzle, and cooperating means including a seat on said bracket and a boss on said nozzle for positioning said nozzle in predetermined relation to said wheel, the boss on said nozzle having a bracket contacting face arranged at an angle to the center line of the nozzle.

In testimony whereof I have hereunto set my hand this first day of August A. D. 1923.

FRANK W. EDWARDS.
